UNITED STATES PATENT OFFICE.

LOUIS B. THOMPSON, OF MARSHALL, MICHIGAN.

WATCH HOLDER.

Application filed April 24, 1925. Serial No. 25,602.

This invention relates to a holder which may be adapted for various purposes or general use, but which is particularly intended to be used by jewelers or watch makers for holding watches which are being kept for repairing.

The objects of this invention are to provide an improved holder for supporting watches or the like; to provide a holder which may be cheaply manufactured and which will be durable and efficient in operation; to provide a holder which is adapted to receive and support watches having various forms of cases; to provide a holder in which a watch may be held in different positions for adjusting the same; to provide a holder which will rigidly support a watch; and to provide such other advantages and novel features as will be described more fully hereinafter.

In the accompanying drawings illustrating this invention,

Figure 1 is a view showing a portion of a rack or board with a plurality of holders arranged thereon;

Figure 2 is a cross sectional view taken on the line 2-2 of Figure 1; and

Figure 3 is a rear elevation of the holder.

My improved holder has a back or body portion 4 having holes 5 at the ends for receiving screws 6 for fastening it to a board or other suitable support 7. The central portion of the back plate or strip is offset or raised as shown in Figure 2. This strip is provided with outwardly projecting fingers 8 which are preferably formed integrally therewith and are struck up from the lower end of the plate as shown in Figures 2 and 3.

The front plate or strip 9 is slidably mounted on the back plate 4 and is provided with outwardly projecting fingers 10 which are adapted to coact with the fingers 8 for holding a watch as indicated at 11. The fingers 10 are preferably formed integrally with the strip 9 and may be struck up from the upper end of the plate, as shown in Figures 1 and 2. The lower end of the plate or strip 9 is cut away so that it fits closely between the projections or fingers 8 and provides shoulders 12 which engage with the hooks 8 to limit the movement of the plate or slide 9 in one direction. The plate or slide 9 has a lug or projection 13 which projects through a slot 14 in the back plate 4 and serves as a guide for the slide. A

spring 15 of the peculiar shape shown in Figures 2 and 3 has a hook 16 at one end which engages with an eye 17 on the back 4 and has a hook 18 at the opposite end which engages with the lug or projection 13 on the slide 9. The spring 15 serves not only to press the slide 9 downwardly or so as to urge the holding fingers 10 toward the holding fingers 8, but also serves as a locking or fastening member to hold the slide in position on the back plate. The lower end of the slide 9 is bent outwardly or provided with a thumb piece 19 for raising it against the tension of the spring 15.

When the watch maker or repair man wishes to insert a watch in the holder, he presses upwardly or against the thumb piece 19 which opens the holder so that the watch may be inserted or placed on the hooks 8, as illustrated in Figure 1, and then as the slide is released the hooks 9 will engage with the upper portion of the watch to hold it in position.

It will be readily seen that the watch will be securely held in such position against vibration and may be held in different positions for adjusting. This is particularly advantageous for the repair man in adjusting a watch after it has been repaired as he will know that the watch will be rigidly held at any fixed position and this will greatly facilitate the proper adjustment or timing of the same. It will also be particularly noted that the holder is adapted for receiving different sized cases of various shapes such as round, hexagonal or other forms, either with or without case lugs or bows. It will be noted that the two principal parts of the device may be readily formed of sheet metal and may be conveniently and cheaply made by means of suitable dies. It will also be noted that changes may be made in the details of construction or form of the device in order to adapt it for different watches or different conditions, therefore I do not wish to be limited to the exact arrangement herein shown and described except as specified in the following claims in which I claim:

1. A watch holder comprising a strip of sheet metal having integrally formed fingers, a second strip slidably engaging with the first named strip and also having integrally formed fingers adapted to coact with the first named fingers for holding a watch or the like, projections on each of said strips, and a spring engaging with said projections

and serving to move the strips to holding position.

2. A holder for watches, comprising a metal strip having an offset central portion and having fingers projecting from the offset portion, a second strip slidably engaging with the first named strip and having shoulders for engagement with said fingers, and also having an extension fitting between said fingers with a thumb piece at the end thereof, fingers projecting from the second named strip and adapted to coact with the first named fingers for holding the watch, a projection on the second named strip which passes through a slot in the first named strip, and a spring engaging with said projection and with the first named strip and adapted

to hold the parts together as well as to move the second named strip to engaging position.

3. A watch holder, comprising a strip of sheet metal having integrally formed fingers, a second strip slidably engaging with the first named strip and also having integrally formed fingers adapted to coact with the first named fingers for holding a watch, said second named strip having a projection passing through a slot in the first named strip, and a spring engaging with said projection and with an eye in the first named strip and serving to move the second named strip to holding position and to fasten the parts together.

LOUIS B. THOMPSON.
